UNITED STATES PATENT OFFICE.

DAVID A. KITCH, OF CHICAGO, ILLINOIS, ASSIGNOR TO CHICAGO PORTRAIT COMPANY, OF CHICAGO, ILLINOIS, A CORPORATION OF ILLINOIS.

DESIGN FOR A PICTURE-FRAME.

SPECIFICATION forming part of Design No. 35,925, dated May 27, 1902.

Application filed December 26, 1901. Serial No. 87,376. Term of patent 7 years.

To all whom it may concern:

Be it known that I, DAVID A. KITCH, a citizen of the United States, residing at Chicago, in the county of Cook and State of Illinois, have invented and produced a new and original Design for a Picture-Frame; and I do hereby declare the following to be a full, clear, and exact description of the same, reference being had to the accompanying drawing, forming a part thereof.

The figure in the drawing represents a front elevation of my newly - designed picture-frame.

The design consists of a picture-frame of the form shown, A A indicating the respective sides thereof, B the top, and C the bottom, part. The different parts of the frame are ornamented as follows: On the top part B is placed a Templar's cross with crossed

swords. On the right side of the frame is placed a keystone emblem of the order of Masons. On the left side of the frame is placed a square and compass interlocked with the letter - symbol G. A Masonic altar is mounted on the bottom part C, and each of the four corners of the frame are ornamented with a shield and eagle device arranged as shown.

What I claim is—

The design for a picture-frame, substantially as herein shown and described.

In testimony whereof I affix my signature in presence of two witnesses.

DAVID A. KITCH.
